(57) **CLAIM**

The ornamental design for a grow light with stand, as shown and described.

DESCRIPTION

FIG. 1 is a front, right and top perspective view of a grow light with stand showing my new design;

FIG. 2 is a left, rear and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the grow light with stand shown in an alternate configuration of use;

FIG. 10 is a perspective view of the grow light with stand shown in an alternate configuration of use; and,

FIG. 11 is an enlarged partial view of FIG. 1.

The broken lines shown in FIGS. 1 and 11 surrounding the detail views are for annotative purpose only and form no part of the claimed design.
